UNITED STATES PATENT OFFICE.

PHILIP N. WALTERS, OF NEW YORK, N. Y., ASSIGNOR TO GACO CORPORATION, OF EAST GREENWICH, RHODE ISLAND, A CORPORATION OF RHODE ISLAND.

BATHING BOAT.

Application filed July 14, 1926. Serial No. 122,297.

The object of this invention is to provide a bathing boat of simple, inexpensive and reliable construction which can be readily folded into small compass for convenience of packing and transportation, and which boat can be as readily unfolded and arranged to afford a buoyant skeleton structure having depending seats that permit the partial immersion of an occupant of the boat while it is in service.

My invention comprises a U-shaped buoyant body of light material, preferably balsa wood, whereof the end and side members are divided in sections and the respective sections are hingedly connected so that they may be folded together, which side members are connected by spaced-apart transverse strips of webbing constituting a depending flexible seat and leg rest that are foldable with the body structure, and which side members are also connected adjacent their forward extremities by detachable clamping bars constituting a substantial tie-member for the structure and affording a step or support for a suitable mast.

The invention also comprises features of construction which will be hereinafter described and claimed.

In the drawings—

Figure 1 is a perspective view of a bathing boat embodying the preferred form of my invention, showing the structure as equipped with a sail and with a sculling or steering paddle.

Fig. 2 is a transverse section of the boat, as on the line 2—2 of Fig. 1.

Fig. 3 is a view of the body of the boat as folded.

Referring to the drawings, 5 designates a transverse stern member from the respective ends of which extend elongated side members 6, the whole being constructed preferably of balsa wood and constituting a light buoyant structure.

The stern member is transversely divided midway between its ends, and the two sections thus formed are hinged together by means of a horizontal hinge 7 which is suitably secured to the bottom of the sections, so that they may be folded together. On the top of the stern sections are secured two mating hinge leaves 8 adapted to receive a pin 9 which, when it is inserted in the mating eye portions of the leaves, effectually locks the two stern sections in

open position. When the pin 9 is withdrawn the stern sections may be folded on their hinge 7, as previously mentioned. The leaves 8 afford metal reinforcing plates against which bear the heads of the bolts or rivets 10 which secure the hinge 7 to the stern sections.

Each of the side members 6 of the buoyant structure is divided between its ends, and the two sections thus formed are connected on their inner sides, by means of a vertical hinge 11, so that the forward section can be swung inwardly and folded against the rearward side section. The outer faces of the two hinged side sections 70 are provided with metal reinforcing plates 12 against which bear the heads of the bolts or rivets 13 which secure the hinge 11 to the side sections.

The corresponding sections of the two side members are connected by transverse webs of flexible material, such as canvas, which are looped to embrace said sections and sag below the same, thus affording a seat 14 and a leg rest 15 for the occupant of the boat. The webs sag below the side members of the structure so that a portion of the body, as well as the legs, of the occupant, is immersed in the water; it being noted that the seat 14 is located adjacent the large and buoyant stern member. The occupant thus faces the open forward end of the boat and his legs and body are subjected to the action of the stream between the side members as the boat progresses.

The side members 6 are rigidly held together, adjacent their forward ends, by means of a pair of tie bars 16 which embrace the side members and are detachably clamped thereto by vertical screw bolts 17. The lower bar is preferably provided on its upper surface with suitably located cross-pieces 18 which serve as inner stops or braces for the forward ends of the side members.

The tie bars 16 are centrally perforated, as at 19, to receive and support a light sectional mast 20 equipped with a suitable sail 21 which can be readily manipulated by the occupant of the boat.

Fastened to the stern member 5 is a rawhide loop 22 to which the locking pin 9 is conveniently attached, which loop is adapted to receive a sculling or steering paddle 23.

100

105

110

When the sectional stern and side members are swung open a U-shaped body is provided. The stern is then locked by means of the pin 9 and the side members are rigidly connected by the tie bars 16, as seen in Fig. 1, thus affording a rigid, light and durable body of great buoyancy, which may be used as a bathing boat, with or without the sail. By removing the mast and sail, if they are used, and then withdrawing the pin 9 and detaching the tie-bars 16, the body of the boat may be folded, as indicated in Fig. 3, and the several parts thus be packed together in small compass.

15 1. I claim—

1. A bathing boat comprising a substantially U-shaped buoyant body composed of a sectional transverse stern member and sectional elongated side members extending therefrom, hinge connections for the adjoining ends of the respective sections, flexible material loosely connecting the side members, and means for locking the respective members in open position.

25 2. A bathing boat comprising a substantially U-shaped buoyant body composed of a sectional transverse stern member and sectional elongated side members extending therefrom, hinge connections for the adjoining ends of the respective sections, flexible material loosely connecting the side members, and means for locking the respective members in open position, said means including a pair of hinge leaves arranged in opposition to the hinge connection for the stern sections, and a detachable pin for said leaves.

30 3. A bathing boat comprising a substantially U-shaped buoyant body composed of a sectional transverse stern member and sectional elongated side members extending therefrom, hinge connections for the adjoining ends of the respective sections, flexible material loosely connecting the side members, and means for locking the respective members in open position, said means comprising a pair of hinge leaves arranged in opposition to the hinge connection for the stern sections, a detachable pin for said leaves, tie-bars embracing the forward side sections, and means for detachably clamping said bars to the side members.

35 4. A bathing boat comprising a substantially U-shaped buoyant body composed of a sectional transverse stern member and sectional elongated side members extending therefrom, hinge connections for the adjoining ends of the respective sections, flexible material loosely connecting the side members, and means for locking the respective members in open position, said means including tie bars embracing the forward side sections, and means for detachably clamping said bars to the side members.

40 5. A bathing boat comprising a substantially U-shaped buoyant body composed of a sectional transverse stern member and sectional elongated side members extending therefrom, hinge connections for the adjoining ends of the respective sections, flexible material loosely connecting the side members, and means for locking the respective members in open position, said means comprising a pair of hinge leaves arranged in opposition to the hinge connection for the stern sections, a detachable pin for said leaves, tie-bars embracing the forward side sections, and means for detachably clamping said bars to the side members.

45 6. A bathing boat comprising a substantially U-shaped buoyant body composed of a sectional transverse stern member and sectional elongated side members extending therefrom, a hinge connection on the under side of the adjoining ends of the stern sections, a pair of hinge leaves on the upper side of the stern member at the adjoining ends of its sections, a detachable pin for said leaves, hinge connections on the inner sides of the adjoining ends of the respective side sections, flexible material loosely connecting the side members, and a rigid tie connection for the forward sections of the side members.

50 Signed at New York in the county and State of New York this seventh day of July, A. D. 1926.

PHILIP N. WALTERS.
